UNITED STATES PATENT OFFICE.

WILLIAM C. WALDA, OF FORT WAYNE, INDIANA.

MOLDING-MACHINE.

1,265,405.

Specification of Letters Patent.

Patented May 7, 1918.

Application filed January 18, 1917. Serial No. 143,014.

To all whom it may concern:

Be it known that I, WILLIAM C. WALDA, a citizen of the United States of America, and resident of Fort Wayne, in the county 5 of Allen and State of Indiana, have invented certain new and useful Improvements in Molding-Machines, of which the following is a specification.

This invention relates to improvements in 10 molding machines particularly of that class used for manipulating bench flasks and the object thereof is to afford a machine of its class having means for accurately separating the flask sections and the pattern from 15 the mold upon the completion of the latter, the operation being commonly known as "parting." And a special object is to provide means for parting the flask and pattern in such manner as to require a lesser 20 degree of skill than is ordinarily required in making a mold, and to effect accurately made molds with greater rapidity than is ordinarily attained where the parting is done by hand manipulation.

25 These objects are accomplished by the construction illustrated in the accompanying drawings, in which:—

Figure 1 is a perspective view of the device;

30 Fig. 2 is a similar view of the same including the bottom board and lower portion of a flask in place, and showing also the parting posts in elevated position;

Fig. 3 is a front elevation of the device 35 upon a larger scale than the former figures;

Fig. 4 is a side elevation partly in vertical section in a plane extending through the character X of Fig. 3.

Fig. 5 is a plan view of the device;

40 Fig. 6 is a perspective view of the upper portion of a flask; and

Fig. 7 is a perspective view of a pattern used in making molds.

Similar characters of reference indicate 45 corresponding parts throughout the several views and referring now to the same:

1 is a frame, horizontally disposed and supported by three legs (2), (3) and (4) respectively which are bolted thereto. The 50 leg (2) extends upwardly beyond the frame (1) and supports at its upper end a shelf (5) intended for lodgment of hand tools and instruments used by the operator. Extending forwardly from the leg (2) between 55 the shelf and frame are adjustable brack-

ets (6) which afford temporary support for the cope (7), or upper portion of the flask, while the pattern (8) is being removed.

From the frame extends a pendant hanger (9) having a bearing (10) at its lower end 60 in which is arranged a vertically movable shaft (11). The bearing (10) is made of sufficient length to insure guidance of the shaft in true vertical directions, it being essential also that the shaft shall fit snugly 65 in the bearing so that the former in its vertical movements will be prevented from shivering at any stage. At the top of the shaft is rigidly fixed a spider (12) having lateral arms (13) and (14), and also a rearwardly extending arm (15). The rear end of the arm (15) is slotted and fits upon a vertical pendant guide (16) and is adapted to move vertically thereon, the purpose of the guide being to prevent the spider from 70 having horizontal play. The arms (13), (14) and (15) are each slotted and support parting posts (17), (18) and (19) respectively, the posts extending through the slots and secured to the respective arms by means 75 of nuts (20). The slots admit of adjustably arranging the position of the posts as may be required to suit the size of the flask used in making the mold. Upon each of the posts is adjustably fixed an engaging member (21) hereinafter referred to.

The frame (1) has lateral arms (22) to which are adjustably fixed gage-members (23) and (24) respectively each of which are also slotted.

Upon the top of the frame are secured 90 parallel bed-plates (25), the same being secured by means of bolts (26) that extend through slots (27) made in the frame.

A foot-lever (28) is pivoted at its rear 95 end to a lug (29) that is fixed upon the leg (2), and the forward end of the lever extends outwardly between the front legs (3) and (4) and is provided with a pedal (30). A yoke (31) is fixed upon the lower end of 100 the shaft (11) and extends laterally therefrom, and a cable (32) is connected therewith and leads therefrom upwardly from each end thereof. Pulleys (33) are arranged in connection with the frame (1) upon the 105 under side thereof, and the cable leading from the ends of the yoke passes over the pulleys and has connection with an equalizing bar (34) that is pivotally connected in the forward portion of the foot-lever (28), 110

the cable passing under the equalizing bar. The purpose of the equalizing bar is to admit of an equal application of lifting force to the opposite sides of the yoke through 5 the medium of the cable when the foot-lever is depressed.

Secured rigidly to the front of the frame is a pendant bar (35) that extends vertically adjacent the foot-lever (28), and has 10 adjustably fixed thereon two stops (36) and (37) respectively that are adapted to be engaged by a jaw (38) that extends diagonally upward from the foot-lever. The connection of the foot-lever with the lug (29) is 15 sufficiently loose as to allow play that will admit of slight lateral movement of the lever so that by shifting the lever sidewise it may be made to pass the stops during its vertical movements, or may be made to 20 selectively engage the stops accordingly as manipulated. The weight of the shaft (11), together with the spider fixed thereon and the parting posts carried by the latter is sufficient to lift the foot-lever by gravitational 25 force through the medium of the cable, and therefore those parts tend to remain in their lowermost position while the foot-lever normally tends upwardly.

In operating the machine, a molder's flask 30 is employed similar to those in ordinary use composed of a cope (7) and drag (7'), and also a bottom board (7''). The cope (7), however, is provided with oppositely disposed ears (39) that project respectively 35 from each end, and also another ear (40) that projects from one side of the cope. It is also necessary to provide the pattern (8) with extending arms (41) at its respective ends and also a third arm (42) from one 40 side thereof. These arms are of sufficient length as to extend beyond the corresponding ends and side of the flask when placed therein, recesses (43) being made in either the cope or the drag to admit of their 45 projection therebetween.

In making a mold, the lower portion is formed in the customary manner with the aid of the usual match-plate and with the pattern in place. The bottom board (7'') is 50 then applied as usual and the drag together with the bottom board is turned over and placed upon the bed-plates (25) of the machine and centered thereon by shifting the drag into contact with the guides (23) and (24). The foot-lever is then depressed so 55 that its jaw engages the stop (36). This last operation will have the effect of elevating the parting posts (17), (18) and (19) so that their tops will be in a plane 60 slightly higher than the top of the drag when the stop (36) is properly adjusted. The upper portion of the mold is then formed by placing the cope over the drag with its ears (39) and (40) resting upon 65 the corresponding tops of the parting posts

so as to be supported thereby. The cope is then filled with sand and is rammed in the usual manner. During the latter operation the drag rests upon the bed-plate while the weight of the cope is borne by the posts, 70 there being a slight space intervening between the two sections of the flask. In parting the mold the operator presses the foot-lever gently downward and engages its jaw with the stop (37) with the result that the 75 posts become elevated and carry with them the cope. Also, the lugs (21) on the posts are so adjusted respectively thereon so as to simultaneously engage the extending arms (41) and (42) of the pattern, correspondingly, at a stage in the upward movement of the posts after the cope has been lifted clear of the pattern, and as the upward movement of the posts continue the pattern is thereby raised from the drag. Inasmuch as the cope is initially formed while supported firmly on the posts, the simultaneous rise of the latter lifts the cope with absolute accuracy and thus breaking of the sand at the parting line of the mold is ob- 80 viated.

After the cope and pattern have been raised by the posts to elevated positions, the former is lifted and set on edge upon the arms (6) that extend from the leg (2). The 85 pattern is then removed and the posts are returned to their lowermost position. While thus positioned the cope and the drag are both conveniently accessible for retouching or any other further hand operations that 90 may be required. The impressions that occur in the mold due to the arms (41) and (42) are stopped off by the ordinary expedient of inserted cores, the cope is then replaced upon the drag, and the mold is disposed of in the usual manner. Variations in patterns of course will require the use of flasks of correspondingly different sizes, and the patterns will necessarily have to be provided with suitable extending arms 105 and the flasks with corresponding notches and ears to suit the peculiarities of the pattern and to conform with the range of adjustments of the various parts of the machine. The pattern and flask herein illustrated are given as an example for the preparation of those parts preparatory to their use with the machine, and I do not confine myself in my present invention to the example shown.

What I claim is:

1. In apparatus of the class described, a supporting frame; a vertically extending shaft mounted centrally in connection with the frame and being vertically movable 125 therein; a spider fixed upon the shaft and having a series of slotted arms; a guide with which the spider engages; a series of parting posts vertically disposed and fixed respectively to the arms of the spider; an en- 130

gaging member adjustably fixed on each post; and a mechanism for vertically shifting the shaft.

2. In apparatus of the class described, a frame adapted to support the drag of a molder's flask; means movable in the frame and adapted to engage and support the cope of a molder's flask; operating mechanism for elevating said means; and a stop for

holding said mechanism at rest at a suitable point to support the cope slightly above the drag while the cope is being rammed.

In testimony whereof I affix my signature, in presence of two witnesses.

WILLIAM C. WALDA.
